CRIBBAGE BOARD

Daniel H. Storey, Wausau, Wis.

Application October 22, 1948, Serial No. 149,241

Term of patent 7 years

(Cl. D34—5)

To all whom it may concern:

Be it known that I, Daniel H. Storey, a citizen of the United States and resident of Wausau, in the county of Marathon and State of Wisconsin, have invented a new, original, and ornamental Design for a Cribbage Board, of which the following is a specification, reference being had to the accompanying drawing, forming part thereof.

Figure 1 is a top plan view of a cribbage board, showing my new design.

Figure 2 is a side elevational view of the cribbage board.

Figure 3 is an end elevational view of the cribbage board.

I claim:

The ornamental design for a cribbage board, as shown.

DANIEL H. STOREY.
